UNITED STATES PATENT OFFICE.

ABE A. HOFFMAN, OF KANSAS CITY, MISSOURI.

COSTUME SLIP.

Application filed January 11, 1926. Serial No. 80,516.

My invention relates to ladies' garments, and more particularly to one of that type commonly termed a "costume slip", comprising a combination bodice and skirt 5 adapted for wear beneath an outer garment.

Garments of this kind, being loose fitting, are usually provided with shoulder straps and draw string for supporting the garment and for ornamentation, or the straps are 10 omitted and the garment supported by an elastic band at the upper edge of the garment and adapted to yieldingly grip the body of the wearer above the bust line. The latter form of garment is serviceable but, the garment being exposed above the bodice or at 15 the yoke of a low cut gown, is unattractive in appearance because of the puckering of the band by the elastic material. Extension of the elastic band entirely around the body 20 does not add to the comfort of the wearer and is unnecessary, one or more short strips of elastic properly placed, being sufficient to support the garment and hold it snugly in place while providing the required expansion to permit the garment to be donned 25 in the usual way.

It is the object, therefore, of the present invention, to provide a garment of the character described, which, while as serviceable 30 as those of the types mentioned, omits their unsightly and uncomfortable features.

In accomplishing this object I have provided the garment hereinafter described and illustrated in the accompanying drawings 35 wherein:—

Fig. 1 is a perspective view of a costume slip embodying my improvements as it appears on the body of a wearer.

Fig. 2 is an enlarged perspective view of 40 the upper portion of the slip, parts being broken away to illustrate attachment and position of the elastic strips.

Fig. 3 is a view partly in section and partly in perspective of the upper edge portion 45 of the garment at one of the sides thereof.

Referring more in detail to the drawings:—

1 designates a slip which, except as herein-after noted, is of the usual construction, comprising a bust band 2 forming a pocket 50 and shoulder straps 3.

Located within the pocket, and concealed by the band 2, at the arm pit positions, are short lengths of elastic strips 4, the ends of which are securely attached to the band by 55 stitching or other fastening means 5 to constitute them permanent parts of the garment, the strips being sufficiently short to lie within the arm pits of a wearer and be concealed by the wearer's arms while the garment is being worn, but of sufficient length 60 to permit the required expansion when being applied over larger portions of the body. While the elastic strips are short, they are 65 strong enough to support the garment, with or without the aid of the shoulder straps and, in any event, to draw the bust band snugly and evenly over the chest and back of the wearer. The chest and back portions of the band, being plain, will not pucker 70 as they would if the elastic extended entirely around the band, the puckering due to the draw in action of the elastic being limited to the elastic containing portions concealed by the arms. 75

Consequently a garment embodying my improvements provides a sightly appearance, with added comfort to the wearer without sacrificing serviceability.

What I claim and desire to secure by 80 Letters Patent is:—

In a garment of the character described, a pocket extending around the top thereof comprising a bust band, short strips of elastic within the band at the arm pit positions with their ends only attached to the pocket, the front and back portions of the band being free from elastic to lie flat against the body of a wearer when the band is drawn to the body by the elastic strips, 85 and shoulder straps having the ends thereof attached to the band adjacent the ends of the elastic strips, so that said elastic strips lie between the ends of the straps and under the arm pits of the wearer thereof and the flat 90 portions of said band extend between said shoulder straps at the front and rear of said garment. 95

In testimony whereof I affix my signature.

ABE A. HOFFMAN.
